(57) CLAIM

The ornamental design for a vehicle cover, as shown and described.

DESCRIPTION

FIG. 1 is a front view of a vehicle cover showing our new design;

FIG. 2 is a left view of the design of FIG. 1; and,
FIG. 3 is a right view of the design of FIG. 1.

The vehicle is depicted in broken lines, to show that it forms no part of the claimed design.
